FIGURE 1 is a perspective view of a control panel for a multi-track tape deck embodying my new design;

FIGURE 2 is a left side view of a control panel for a multi-track tape deck shown in FIGURE 1;

FIGURE 3 is a right side view of a control panel for a multi-track tape deck shown in FIGURE 1; and

FIGURE 4 is a front view of a control panel for a multi-track tape deck shown in FIGURE 1.

The dominant features of my design reside in the portions shown in full lines. The fragmentary broken lines representing the housing are shown for illustrative purposes only.

I claim:

The ornamental design for a control panel for a multi-track tape deck, substantially as shown and described.
